(57) **CLAIM**

The ornamental design for an earplug handle, as shown and described.

DESCRIPTION

FIG. 1 is a perspective view, showing the new design for an earplug handle;

FIG. 2 is a front view thereof;

FIG. 3 is a left side view thereof, the right side view being the same as the left;

FIG. 4 is a top view thereof; and,

FIG. 5 is a bottom view thereof.

The broken line showing forms no part of the claimed design.
